UNITED STATES PATENT OFFICE.

HENRY M. COLVIN, OF KANSAS CITY, MISSOURI.

KEY COMPACT.

Application filed May 22, 1926. Serial No. 110,942.

This invention relates to a carrying case for keys, or the like, and has for its primary object the provision of what is preferably termed a "key compact" constructed with a rigid case within which may be housed suitable means for supporting a large number of keys in their proper position and relation to each other.

One of the primary objects of my invention is the contemplation of a key compact which will hold the keys firmly in position to preclude the same from becoming disarranged or rattling when the compact is closed and carried in the purse or pocket.

Still another object of the instant invention is to provide novel means which may be adjusted for holding each, or all of the keys, in their proper position within the key compact.

Many minor objects will appear during the course of the detailed specifications referring to the accompanying drawings in which:

Figure 1 is a face view of a key compact made in accordance with my invention and showing one side thereof in an opened position.

Fig. 2 is a vertical cross-section of the compact taken on line 11-11 of Fig. 1 with the compact in the closed position.

Fig. 3 is a horizontal cross-section of the compact taken on line 111-111 of Fig. 2.

Fig. 4 is a top edge view of the compact showing the attachment of the several key-carrying hooks, and,

Fig. 5 is an enlarged perspective view of one of the key retaining clips entirely removed from the compact.

Similar reference characters refer to like parts throughout the several views and the numerals 6 and 7 designate the back and cover, respectively, of the compact case, the cover being hingedly secured to the back along one side as at 8 and adapted to be locked in the closed position by the well-known latch members 9 and 10, respectively.

The case of the compact may be pressed or otherwise formed of sheet metal so that it presents a rigid or non-collapsible housing for the keys to be carried.

It is well known that key containers, pouches, etc. permit the keys to bunch, overlap and become entangled as the same is being carried. Women find it difficult to procure a neat key carrying case and it has been found extremely desirable to make

this compact from German silver or cheap metals which may be coated or plated with a precious or semi-precious metal. Within the hollow casing of the compact is carried the means, made in accordance with this invention, for retaining the key 12 in its proper position with respect to other keys carried in the compact therewith. To properly hold the keys so that they may be turned out away from the back 6, a plurality of hooks 13 are provided, each having means 14 at their upper end for engaging a short pintle 15, formed integrally with the upper edge of back 6 in the manner shown in Fig. 4. This method is properly carried out by cutting away a small portion on each side of the pintle to permit the attaching means 14 to freely engage the same. The hooks 13 are of the ordinary spring type and key 12 may be slipped on in the well-known manner.

As an embodiment of one of the main features of my invention, the means for holding or retaining a key or keys, 12 in their proper position, has been illustrated herein to be a spring plate 16 rigidly secured by rivets or analogous means 17 to the back 6 of the compact. This spring plate 16 has a plurality of slots 18 formed therein which extend downwardly from the upper or free end thereof to a point spaced from the lower, or attached edge. These many slots 18 are parallel and are formed at intervals throughout the entire length of plate 16 and each are adapted to receive a spring clip 19 which is provided with a foot 20 to slide behind spring plate 16 whereby it is held against the inner surface of the back 6. This foot 20 may extend on each side of the main portion of the clip 19 as shown in Fig. 5, and aids to securely hold the upper or key engaging jaw 21 thereof in the proper position. It is preferred to use two of these clips with each key and through the use of many slots 18 their distance apart may be varied according to the thickness or width of the particular key to be hung on the hook 13 thereabove. Clips 19 are removable and may be inserted in any slot 18 along the length of plate 16. The same will not rattle or become noisy when not in use because foot 17 holds them securely in position against movement.

It is understood that the specific embodiment of my invention may be varied considerably from the terms of this specification and that many modifications may be made.

without departing from the spirit of the invention or scope of the appended claims.

What I claim and desire to secure by Letters Patent of the United States is:

- 5 1. A key compact of the class described comprising a back and cover member hingedly attached along one side to form a hollow casing, a plurality of key carrying hooks pivotally carried by said back member along its 10 upper edge, a slotted plate carried within said casing and adjustable clips carried by said plate for engaging each key carried by said plurality of hooks.
- 15 2. In a key compact of the class described having a plurality of pivotally mounted key carrying hooks and a means for securing each key carried by said hooks in its proper relative position including a slotted resilient plate and a plurality of clips carried by said 20 plate adapted to grip the sides of each key.
- 20 3. In a key compact of the class described having a plurality of pivotally mounted key carrying hooks and means for securing each key carried by said hooks in its proper rela-

tive position including a slotted resilient plate and a plurality of clips adapted to releasably engage the keys carried by said hooks, said clips being removably mounted in the slots formed in the resilient plate.

4. In a key compact of the class described, 30 a slotted resilient plate and key engaging clips carried in the slots of said plate, each clip having a foot portion engaged by said plate along each side of its respective carrying slot.

5. In a key compact of the character described, means for carrying a key to permit movement from the housed to the unhoused position including a swingable hook supported adjacent the edge of the compact and 40 means for securing the key against movement including a pair of resilient clips removably mounted on the wall of said compact below said hook and adjacent the free end of the key supported by said hook. 45

In testimony whereof I hereunto affix my signature.

HENRY M. COLVIN.
